UNITED STATES PATENT OFFICE.

CHRISTIAN KRÄMER, OF BERLIN, GERMANY, ASSIGNOR TO GENERAL ELECTRIC COMPANY, A CORPORATION OF NEW YORK.

MOTOR-CONTROL SYSTEM.

1,042,692.

Specification of Letters Patent. Patented Oct. 29, 1912.

Application filed June 3, 1912. Serial No. 701,118.

To all whom it may concern:

Be it known that I, CHRISTIAN KRÄMER, a subject of the Emperor of Germany, residing at Berlin, Germany, have invented 5 certain new and useful Improvements in Motor-Control Systems, of which the following is a specification.

This invention relates to devices for controlling electric motors and has for its object 10 the provision of means whereby an electric motor may be controlled from a remote point in a simple and reliable manner.

My invention relates more specifically to the control of motors which are employed 15 for operating rudders, searchlight projectors and the like, the object being to provide means whereby the movement of the transmitting mechanism in the hands of an operator at a remote point will be reproduced at 20 the motor. Devices of this kind have been commonly used, but some of them have the objection that a large number of conductors are necessary between the transmitting and receiving stations in order to obtain an equal 25 number of control positions. The transmitting and receiving stations are frequently long distances apart and the provision of a large number of conductors is not only inconvenient, but also expensive.

30 One of the objects of my invention, therefore, is to reduce the number of conductors, at the same time insuring accurate and efficient control throughout a large number of control points.

35 Other objects and purposes of my invention will appear in the course of the following specification in which I have shown my invention embodied in concrete form for purposes of illustration.

40 In the accompanying drawing which illustrates my invention in concrete form, Figure 1 shows diagrammatically the form of device to which my invention is to be applied; Fig. 2 is a diagrammatic view of one form of my 45 invention; Fig. 3 is a view of the apparatus similar to that shown in Fig. 2; and Figs. 4, 5 and 6 are modified forms of my invention.

50 Referring first to Fig. 1, it will be seen that this figure represents a typical form of apparatus to which my improvement is applicable. In this figure, A represents the armature and f and f' the two fields of the motor, either one of which may be in circuit to drive the motor in the forward or reverse 55 direction. This motor is controlled from a

remote point by a transmitting device T consisting of a plurality of contacts, a, b, c, d, e, and a controlling contact arm 10 which is moved over the contacts by the operator. The receiving device R consists of the controller C driven by the motor in any manner, as, for instance, through the worm gearing shown. The controller consists of two conducting segments 11 and 12 insulated from each other. For purposes of illustration, I have shown two segments separated by an air space, although, of course, in practice other forms of insulation may be more suitable. Coöperating with these contacts are a plurality of brushes, a', b', c', d', e', connected by wires with the contacts on the transmitting device having corresponding reference characters. These brushes are of less width than the space between the segments 11 and 12, so that when each brush 75 arrives opposite the insulating space the circuit will be broken through the fields f and f', which are connected with the segments 11 and 12 by brushes 13 and 14. It will be seen that with the parts in the position shown no current can flow to the field of the motor since the contact c' is in the off position. If, however, the arm 10 is moved on to contact d then a circuit will be completed from the positive side of the line through 80 the contact d, thence to contact d', field f', motor armature, to the other side of the line. This will cause the motor to rotate in the direction indicated by the arrow until the brush d' is opposite the space, whereupon the motor will stop. In like manner, if the controller is moved on to the contact e the controller may be driven by the motor a corresponding amount until the circuit is opened at the contact e'. If the contact 85 arm 10 is moved to the left into engagement with the contacts b or a the controller will be moved in the opposite direction by the energization of the field f. It will be observed that with this device only as many 90 positions can be transmitted from the transmitting device to the motor as there are conductors extending between the two devices; in this case five.

In Fig. 2 I have shown means whereby the number of positions transmitted may be greatly increased without substantially increasing the number of transmitting wires. Referring to this figure, which is diagrammatic merely, the contacts a, b, c, d, e of the 105

transmitting device T are connected with the corresponding contacts a' , b' , c' , d' , e' of the receiving device R, by wires 15, 16, 17, 18 and 19 through the resistances 20. Contacts a , b , c , d and e in this case may be stationary, while the movable part of the transmitting device consists of the two contact plates 21 and 22 which are spaced from each other a distance which is greater than the width of the coöperating contacts. On each side of the contacts a' , b' , c' , d' , e' are contact plates 23 and 24 connected with the contact plates 21 and 22 by wires 25 and 26 and the fields f and f' of the motor are connected with conductors 27 and 28 at 29 and 30. Current is supplied to the receiving device R through the device T' consisting of a contact arm connected with the positive side of the line and coöperating with the contacts g , h and i . These contacts g , h and i are connected respectively with brushes g' , h' and i' , on the transmitting device by three wires. The brushes g' , h' , i' are spaced apart a distance equal substantially to the distance between the contact plates 23 and 24. The spacing of the brushes is such that when the brush h' is in contact with the contact a' the brush i' is at the beginning of contact plate 24. With the parts in the position shown in Fig. 2 the field circuit of the motor is open at the contact a . If, however, the movable part of the transmitting device, namely, the contacts 21 and 22, is moved to the right the circuit will then be closed from the positive side of the line to the contact h , thence to brush h' on the receiving device and contact a' , thence wire 15 and contact plate 21 to wire 25 and field f to the negative side of the line. This will cause the receiving device, consisting of the plates 23 and 24, and the intervening contacts, to move to the left until the brush h' engages contact b' . In this position the motor will be stopped, since the circuit is opened at the brush b . In like manner, as the transmitting device is moved through the five positions, the receiving device will be correspondingly moved until the contact a' engages the brush g' . If now the auxiliary transmitting device T' is moved onto the contact g then the brush g' will be supplied with current and the receiving device will be moved through five steps more. In the same way if the auxiliary transmitting device is moved so that the contact i is connected with the positive side of the line, then the brush i' will be supplied with current and five more positions will be provided. In other words, the number of positions the motor will be afforded by said device will be the product of the number of conductors between the receiving and transmitting device, in this case five, and the number of conductors from the supply circuit to the receiving device, which in this case is three,

making fifteen positions. It will be understood, of course, that these controlling devices are in practice circular in form so that the contact e of the device T, for instance passes off the insulating space between contacts 21 and 22 just as contact a passes onto it. This is best understood by reference to Fig. 3, in which the various controlling devices are shown in proper form and relation to each other. In this case the controller of the receiving device consists of the plates 23 and 24 separated by the four contacts a' , b' , c' , d' , which are connected with the brushes a , b , c and d of the transmitting device T by means of the four wires. Contact plates 21 and 22 are movable with the arm 10. The auxiliary transmitting device T' consists of five contacts g , h , i , j , k connected with brushes g' , h' , i' , j' , k' of the receiving controller by five separate wires as shown. The movable arm of the auxiliary transmitting device T' is connected with the positive side of the line. By moving the arm 31 into engagement with any one of the contacts g , h , i , j , k , any one of the brushes g' , h' , i' , j' , k' will be energized. The fields f and f' are connected with plates 23 and 24 by brushes 32 and 33. The two devices T and T' are mechanically connected with each other so that to each half revolution of the arm 10 the arm 31 will complete a revolution, that is, the ratio of the movements between the two arms is two to five. With the parts in the position shown in Fig. 3 no circuit is closed since the brush i' which is energized connects with brush contact d' which is deenergized. If now the arm 10 is moved to the right the segment 21 will move into engagement with the brush d so as to be in connection with brush 32 and field f . Then the field f of the motor will be energized through brushes i and i' to contacts d' , d , and contact 34 to field f' . This will cause the motor to rotate so as to rotate the controller drum in the direction of the arrow until the brush i' passes off contact d' and onto contact c' . The motor will then be stopped, since the contact c' is not now in circuit. In like manner, by moving the arm 10 so that the segment 21 engages the brushes c , b and a respectively, the controller will be correspondingly moved. In the meantime the arm 31 of the transmitting device T' is moved forward along the contact i until it engages the contact j , whereupon the brush j' will be energized and the contacts a' , b' , c' and d' will pass under this brush and operate as before. In this case it will be seen that for each position of the transmitting device T' four positions will be transmitted. Since there are five positions of the transmitting device T', twenty positions in all can be transmitted to the receiving controller.

In Fig. 4 I have shown a slight modifi-

cation which consists principally in employing the Ward-Leonard system of control instead of controlling the motor directly. The two windings f and f' are the field windings of the generator G which furnishes current to the armature A of the motor. The motor will be driven in one direction or the other, depending upon which of the two fields f or f' is energized.

10 In Fig. 5 I have shown another modification in which the two coils f and f' are the coils of a relay, either of which may be energized to cause the relay to close the circuit to connect the motor for rotation in one direction or the other.

15 In the arrangement shown in Fig. 6 not only the transmitting mechanism is divided into two parts, devices T and T', but the receiving mechanism is likewise divided into 20 two parts, R and R'. The controlling device T', which is connected with the positive side of the line, is provided with a plurality of contacts, A', B', C', D', E' connected by wires with corresponding brushes 25 A, B, C, D and E on the receiving device R'. While in the form shown in Fig. 3 a

30 number of contacts are inserted between the segments 23 and 24 for producing the intermediate positions between the main positions, in the present instance there is only a single contact bar 35 having a length equal to the distance between the brushes A and B, etc. This segment 35 is connected by a brush to wire 36 to the pivotal point of the 35 movable member of the transmitting device T. This transmitting device T consists of five contacts, F', G', H', I', J', connected by wires with corresponding brushes F, G, H, I, J, K on the receiving controller R.

40 This controller is arranged as in Fig. 1 and consists merely of two segments 11 and 12 and is driven by the motor M. The brushes 32 and 33 are likewise in engagement with the contact segments 11 and 12 and connect 45 through the resistances r and r' with the fields f and f' , which in this instance I have shown merely as being the fields of the exciter X for the generator Y which supplies the motor. The two receiving devices R

50 and R' are connected together mechanically in such a manner that during one-half revolution of the receiving device R the receiving device R' rotates half a brush. The two transmitting devices are so connected 55 mechanically that during a complete rotation of the device T the transmitting device T' is rotated one contact. With the parts as shown in the drawing the circuit is from the positive side of the line through

60 the contact C', to the brush C of the receiving device R', segment 35, conductor 36, to the contact H' and to brush H. If now the arm of the transmitting device T is moved on to contact I' then the brush I of the receiving device R will be energized and cur-

rent will pass to the segment 12, brush 33, resistance r' and field f' . This starts the motor thereby shifting the segment 12 to such a position as to interrupt the circuit at contact brush I. This process will be repeated until the contact device T is moved to contact J'. When the arm of device T is moved onto contact F' arm of the device T' moves from contact C' to contact D'. While this movement is taking place, 70 the receiving device is in position for the current to pass from the positive side of the line, through the transmitting device T', contact D', through the brush D of the receiving device and from there directly to the field f' of the exciter. The motor M is thus started and rotates the contact segments 11 and 12 of the receiving device R in the direction of the arrow. At the instant when the segment 11 connects the 75 brushes F and H the receiving device R rotates one brush division farther. This is caused by the fact that the brush D simultaneously engages the segments 23 and 35. This causes a divided current to flow 80 through the conductor 36, contact F', contact F, thence to the resistance r , and field f . Since, however, on account of the resistance r , the energization of the field f is less than that of the field f' , the motor will continue 85 to rotate in the same direction until the brush F passes off the segment 11. By further movement of the transmitting device T the receiving device R will be moved correspondingly. Attention is here called to the 90 function of the resistances r and r' . The transmitting device T must be adapted to be moved to any position without regard to the position of the contact and during these movements current interruptions must not 95 occur in passing from one to the other. This is obvious since otherwise the controlling arm might stop at some position, as for instance between contacts J' and F', and the 100 controlling arm of the transmitting device T' would find itself between the contacts D' and E'. If in this case interruption of current should occur the motor M would not be moved and the device would be destroyed. Thus in order that no interruption of current may take place two contacts must be 105 engaged simultaneously. Assume in this case that the arm of the transmitting device T' touches simultaneously the contacts C' and D' while the controlling arm of the 110 transmitting device T touches simultaneously contacts J' and F', the receiving device R being in the position indicated on the drawing. Current flows from the positive side of the line through the contacts 115 C' and D' in parallel, thence to the contacts C and D in parallel. From the brush D current passes directly to the field f' of the motor, exciting the latter while from the brush C current passes through the conduc- 120

125

130

4

tor 36 to the brushes J' and F', and thence in parallel to the brushes J and F of the receiving device R. The field f is thus energized through the resistance r and since the 5 resistance r' is practically short circuited, the field f' will be almost fully energized. If the resistance r were not provided the two fields would be equally and oppositely energized. The motor therefore rotates in a 10 direction corresponding to the excitation of the field f' but the movement is correspondingly slower. The motor will therefore move until the contact segment 11 connects the brushes F and J, brushes C and D at 15 the same time both touching the contact 35. At this instant the two fields f and f' are equally and oppositely excited and the motor and receiving device remain in this intermediate position which corresponds to the 20 intermediate position of the transmitting device. It will thus be seen that by the use of the resistances r and r' movements are effective also at the intermediate positions.

It will thus be seen that I have provided 25 means whereby the motor driving the device such as a rudder, projector or the like, may be controlled from a remote point through a large number of positions by the use of a relatively small number of connecting 30 wires and while I have described my invention as embodied in concrete form and operating in a specific manner for purposes of illustration, it should be understood that I do not limit my invention thereto, since various modifications thereof will suggest 35 themselves to those skilled in the art without departing from the spirit of my invention, the scope of which is set forth in the annexed claims.

40 What I claim as new and desire to secure by Letters Patent of the United States, is,—

1. The combination with an electric motor, of a controller therefor driven by the motor, a transmitting device, a plurality of 45 conductors connecting said controller with the transmitting device, a plurality of conductors supplying current from the source of supply to the controller, and connections whereby said controller is moved by the motor in response to a movement of the transmitting device to a number of positions equal to the product of the two sets of conductors.

2. The combination with an electric motor, of a controller therefor driven by the motor having a plurality of contacts, a transmitting device provided with corresponding contacts, a plurality of conductors connecting the contacts on the controller 60 with the corresponding contacts on the transmitting device, a plurality of conductors supplying current from a source of supply to the contacts on the controller, and connections whereby said controller is moved by the motor in response to a movement of

the transmitting device to a number of positions equal to the product of the two sets of conductors.

3. The combination with an electric motor, of a controller therefor driven by the 70 motor and provided with a plurality of contacts, a transmitting device provided with corresponding contacts, a plurality of conductors connecting the contacts on the controller with the corresponding contacts on the transmitting device, a plurality of conductors connecting the controller with a source of supply, a switch for shifting from one supply conductor to another, and connections whereby the controller is moved 75 throughout the range of its contacts in response to corresponding movement of the transmitting device when one supply conductor is in circuit and repeats the operation when another supply conductor is in 80 circuit.

4. The combination with an electric motor, of a controller therefor driven by the 90 motor and provided with a plurality of contacts, a transmitting device provided with corresponding contacts, a plurality of conductors connecting the contacts on the controller with the corresponding contacts on the transmitting device, a plurality of conductors connecting the controller with a 95 source of supply, a switch for shifting the connection of the source of supply from one conductor to another, mechanical connections between the switch and said device whereby the latter is moved over a number 100 of contacts while the former is being moved to its next contact, and connections whereby the controller is moved to a number of positions equal to the product of the said sets of conductors in response to corresponding 105 movements of the transmitting device.

5. The combination with an electric motor and a controller therefor driven by the motor having a plurality of contacts, a transmitting device comprising a main contact device having contacts corresponding with those on the controller, and an auxiliary contact device mechanically connected therewith so that the former moves throughout its entire range of movement while the latter is moving to the next contact, a plurality of conductors connecting the contacts on the controller with corresponding contacts on the main contact device, a plurality of conductors supplying current from the auxiliary contact device to the contacts on the controller, and connections whereby the controller is moved throughout its range of contacts in response to a corresponding movement of the main contact device in position of the auxiliary contact device.

6. The combination with an electric motor and a controller therefor driven by the motor and provided with a plurality of contacts, a transmitting device provided with 125

contacts corresponding with those on the controller, a plurality of conductors connecting the contacts of the controller to corresponding contacts on the transmitting device, brushes connected with a source of supply coöperating with the controller contacts and arranged so that one brush engages the first contact when another passes off the last contact, a switch for shifting the connection of the source of supply from one brush to another, and connections whereby a movement is given the controller throughout its range of contact in response to movement of the transmitting device as each brush is connected to the supply circuit.

7. The combination with an electric motor and a controller therefor driven by the motor having a plurality of contacts, a transmitter comprising a main contact device having contacts corresponding with

those on the controller, an auxiliary contact device connected with a source of supply, mechanical connections between said two devices whereby the main contact device is moved throughout its entire range of movement while the auxiliary device is moving to its next contact, a plurality of conductors connecting the contacts on the controller with corresponding contacts on the main contact device, a plurality of conductors between the auxiliary contact device and the controller arranged so that they supply current one after another to the successive contacts of the controller.

In witness whereof, I have hereunto set my hand this 14th day of May, 1912.

CHRISTIAN KRÄMER.

Witnesses:

RICHARD VENMANN,
WALTHER REINHARDT.
